(57) **CLAIM**

The ornamental design for an plush toy, as shown and described.

DESCRIPTION

FIG. 1 is a perspective view of a plush toy showing a new design;

FIG. 2 is a front view thereof;

FIG. 3 is a back view thereof;

FIG. 4 is a side view thereof;

FIG. 5 is an opposite side view thereof;

FIG. 6 a top view thereof;

FIG. 7 is a bottom view thereof;

FIG. 8 is a perspective view of a second embodiment of plush toy showing a new design;

FIG. 9 is a front view thereof; and

FIG. 10 is a back view thereof;

FIG. 11 is a side view thereof;

FIG. 12 is an opposite side view thereof;

FIG. 13 a top view thereof;

FIG. 14 is a bottom view thereof;

FIG. 15 is a perspective view of a third embodiment of plush toy showing a new design;

FIG. 16 is a front view thereof; and

FIG. 17 is a back view thereof;

FIG. 18 is a side view thereof;

FIG. 19 is an opposite side view thereof;

FIG. 20 a top view thereof;

FIG. 21 is a bottom view thereof;

FIG. 22 is a perspective view of a fourth embodiment of plush toy showing a new design;

FIG. 23 is a front view thereof; and

FIG. 24 is a back view thereof;

FIG. 25 is a side view thereof;

FIG. 26 is an opposite side view thereof;

FIG. 27 a top view thereof; and,

FIG. 28 is a bottom view thereof.

The broken line showing of the plush toy is for the purpose of illustrating portions of the article that forms no part of the claimed design.
